UNITED STATES PATENT OFFICE

95,041

DESIGN FOR A COMBINED CHARGING AND TESTING APPARATUS AND STOCK STAND

Benjamin F. W. Heyer, Belleville, N. J.

Application November 16, 1934, Serial No. 54,053

Term of patent 14 years

To all whom it may concern:

Be it known that I, Benjamin F. W. Heyer, a citizen of the United States, residing at Belleville, in the county of Essex, State of New Jersey, have invented a new, original, and ornamental Design for a Combined Charging and Testing Apparatus and Stock Stand, of which the following is a specification, reference being had to the accompanying drawing, forming part thereof.

The figure is a perspective view of a combined charging and testing apparatus and stock stand, showing my new design.

I claim:

The ornamental design for a combined charging and testing apparatus and stock stand, as shown.

BENJAMIN F. W. HEYER.
